UNITED STATES PATENT OFFICE.

HENRY J. MONTGOMERY, OF SILVER CREEK, NEW YORK.

FURNITURE.

No. 818,201.

Specification of Letters Patent. Patented April 20, 1909.

Application filed October 3, 1908. Serial No. 456,010.

To all whom it may concern:

Be it known that I, HENRY J. MONTGOMERY, of Silver Creek, in the county of Chautauqua and State of New York, have invented certain new and useful Improvements in Furniture; and I do hereby declare the following to be a full, clear, and exact description of the invention, such as will enable others skilled in the art to which it appertains to make and use the same.

My invention relates to an improvement in furniture and more particularly to spring seats for chairs, sofas, etc., the object being to provide means for holding the springs in their approximately upright position without interfering with, or materially limiting their capacity to yield vertically under a weight.

A further object is to so construct the chair bottom that the upholstered or cushion portion thereof will be entirely independent of the chair frame.

With these objects in view my invention consists in a series of connected springs, and a guiding or sustaining rod secured to the front row of springs and provided with bent or crank ends pivotally connected to the chair frame.

My invention further consists in a series of connected springs, an upholstered cushion thereon, and a fabric covering depending from the spring frame and secured to the chair frame, the upholstered cushion being stitched at its ends to the fabric covering.

My invention further consists in the parts and combinations of parts and in the details of construction as will be more fully explained and pointed out in the claims.

In the accompanying drawings, Figure 1 is a view in perspective of a chair embodying my improvements. Fig. 2 is a plan view of the same with the cushion removed showing the springs and their connections and the guiding or sustaining rod for guiding the spring seat in its movements. Fig. 3 is an enlarged view showing the guiding rod attached to the frame, and Fig. 4 is a view of a modification.

My improvement is applicable to furniture of any and all kinds wherein springs are employed under the upholstered portions and while I have shown and described it in connection with a chair bottom, I would have it understood that I do not confine its use to chairs.

1 represents the frame of a chair and 2 the webbing of interlaced strips of fabric secured at their ends to the under side of the frame 1 and forming a support for the springs 3, which latter are of the usual form employed for this purpose. These springs are connected into a single series conforming approximately to the shape of the chair bottom, by the longitudinal strips 4, connected by suitable metallic clips 5 to the upper coils 65 of each row of springs, and transversely by the rods 6, which are similarly connected to the upper coils of each row of springs. The entire series of springs are encircled by the rim rod 7 which is secured to the upper coils 70 by metal clips or by burlap or cord as desired. The springs so assembled and connected, extend well forward to the front of the chair frame and, are connected at the front to the crank rod 8, the latter being connected to the 75 rim rod 7 by the metal or equivalent clips 9, or if preferred may be connected by cords or any other suitable material. The spring frame consisting of the series of connected springs, the rim rod, and the crank rod, are 80 connected to the frame of the chair by strips of webbing 10 which latter serve to simply limit the upward movement of the springs. The crank rod 8 is free to turn in the clips 9 and is provided with rearwardly and outwardly bent ends constituting crank arms. In Fig. 2 these arms are bent inwardly, as at 11 and outwardly as at 12, the outwardly extending portions 12 resting in openings formed in the inner sides of the arms of the 90 chair. In the construction shown in Fig. 4, the rim wire 7 is bent at its forward end so as to project laterally and forwardly in front of the arms or arm posts, and the crank rod 8^a is provided with rearwardly projecting members 95 11^a, and inwardly projecting members 12^a, which latter rest in openings formed in the outer faces of the arms or arm posts of the chair.

In the construction shown in Figs. 1, 2 and 10^a the spring seat terminates at its front approximately in line with the arm posts of the chair, whereas in the construction shown in Fig. 4, the spring seat projects in front of the arm posts, thus permitting the latter to be 105 set back some distance from the front edge of the chair frame.

With these constructions it will be seen that the springs may, when under pressure, yield or give vertically but are prevented 110

from a rearward deflection by the crank rods 8 and 8^a. These rods being mounted to rock, move in the arc of a circle, and while they permit free vertical, and necessarily some slight rearward movement, operate to prevent the springs and cushion top from being forced rearwardly by any ordinary weight that may be seated thereon.

Covering the springs and passing over the 10 rim wire 7 is the covering 15 which latter constitutes the bottom member of the cushion. This covering 15 extends down and is secured at its lower edge to the chair frame thus concealing the springs and rim wire, assisting the 15 strips 10 in limiting the upward movement of the spring bottom, and for holding the latter under tension, if it be so desired. The top member 14 of the cushion is sewed to the edge wire 8, and to the bottom member 14, 20 the filling being inserted between the two members 14 and 15.

The bottom thus constructed may be upholstered in leather, fabric or any materials usually employed for this purpose.

25 It is evident that changes in the construction and relative arrangement of the several parts might be made without avoiding my invention and hence I would have it understood that I do not restrict myself to the particular construction and arrangement of parts shown and described, but,—

Having fully described my invention what I claim as new and desire to secure by Letters-Patent, is,—

1. The combination with a series of connected springs and a rim wire embracing the entire series and connected to the outer springs, of a cushion bottom covering the springs and secured at its lower end to the chair frame and a cushion top secured by 40 stitching to the rim wire and also to the cushion bottom.

2. The combination with a series of connected springs and rim wire embracing the entire series and secured to the outer springs, 45 and a crank rod loosely connected to that portion of the rim wire adjacent to the front springs the bent ends of said crank rod projecting rearwardly and loosely mounted in the front portion of the chair frame, of a 50 cushion the bottom of which overlaps the rim and crank rods and secured at its lower edge to the frame of the chair, the top member of the cushion being secured to the rim wire and to the bottom member.

55 In testimony whereof, I have signed this specification in the presence of two subscribing witnesses.

HENRY J. MONTGOMERY.
